UNITED STATES PATENT OFFICE.

LE ROY C. FAIRCHILD, OF NEW YORK, N. Y.

DESIGN FOR A CIGAR-CUTTER CASE.

SPECIFICATION forming part of Design No. 14,817, dated February 26, 1884.

Application filed October 16, 1883. Term of patent 7 years.

To all whom it may concern:

Be it known that I, LE ROY C. FAIRCHILD, of the city and State of New York, have invented and produced a Design for Cigar-Cutter Cases, of which the following is a specification.

In the drawings, Figures 1, 2, and 3 are elevations at the respective sides of the said cigar-cutter case, and Fig. 4 is an end view.

This design relates to the shape and configuration of the exterior of the cigar-cutter cases. These cases are often worn as a charm upon the watch-chain, and hence require to be of an ornamental character. The exterior or case is of the general configuration of a bottle. The end corresponding to the neck of the bottle is provided with an ornamental collar, *b*, and the neck *c* of the case is a gradual taper. The

body *d* is cylindrical, or nearly so, and the bottom end is open, and there is a conical interior recess, as shown at *e*. There is a pear-shaped opening in the case at *a*, and a disk at *f*, and a ring, *i*, at the small end of the case. The ring *i* at the small end completes the appearance of the cigar-cutter case. 25

I claim as my design—

The design of the shape and configuration of the cigar-cutter case, substantially as set forth.

Signed by me this 15th day of October, A. 30
D. 1883.

LE ROY C. FAIRCHILD.
